UNITED STATES PATENT OFFICE.

ANDREW COCHRAN, OF TRENTON, NEW JERSEY.

DESIGN FOR A WATER-CLOSET BOWL.

45,055.

Specification for Design.

Patented Dec. 23, 1913.

Application filed October 15, 1913. Serial No. 795,373. Term of patent 14 years.

To all whom it may concern:

Be it known that I, ANDREW COCHRAN, a citizen of the United States, and a resident of Trenton, Mercer county, New Jersey, have invented a new, original, and ornamental Design for Water-Closet Bowls, of which the following is a specification, reference being had to the accompanying drawing, showing a perspective view of the bowl forming the subject of my design.

I claim:

The ornamental design for a water closet bowl, as shown.

ANDREW COCHRAN.

Witnesses:

ELLIS L. PIERSON,
CATHARINE PIPPEL.
